R. L. HOLLIMAN AND J. W. COLLINS.

DRIVER FOR DISK TALKING MACHINES.

APPLICATION FILED JUNE 29, 1921.

1,406,864.

Patented Feb. 14, 1922.

UNITED STATES PATENT OFFICE.

ROBERT LEWIS HOLLIMAN AND JOHN WORTH COLLINS, OF VALDOSTA, GEORGIA.

DRIVER FOR DISK TALKING MACHINES.

1,406,864.

Specification of Letters Patent. Patented Feb. 14, 1922.

Application filed June 29, 1921. Serial No. 481,437.

To all whom it may concern:

Be it known that we, ROBERT L. HOLLIMAN and JOHN W. COLLINS, citizens of the United States, both residing at Valdosta, in the county of Lowndes and State of Georgia, have invented certain new and useful Improvements in Drivers for Disk Talking Machines; and we do hereby declare the following to be a full, clear, and exact description of the invention, such as will enable others skilled in the art to which it appertains to make and use the same.

The present invention relates to improvements in drivers for disk talking machines or the like, and has for an object to provide an improved driving device for the rotary table upon which the disk record is received, which driving device is united with the actuating motor, one element of the driving device being combined as a unit with the motor and being movable therewith radially of a driving disk whereby to vary the speed ratio.

Another object of the invention resides in combining a motor and friction gear in a compact, unitary arrangement assembled and mounted so as to be capable of a sliding movement with respect to the disk which the friction gear engages and drives.

A further object of the invention resides in combining and arranging the several parts of the apparatus so that the motor and friction gear driven and supported thereby will be contained within the cabinet of the phonograph and supported upon guides therein for sliding movement, which sliding movement is effected by manipulating means extending upon the exterior of the cabinet and combined with a latch to hold the parts in the adjusted position.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a fragmentary vertical sectional view through a phonograph cabinet showing the improved driving device;

Fig. 2 is a bottom plan view thereof with certain parts removed for clearness;

Fig. 3 is an end view of the motor support and guideways; and

Fig. 4 is a top plan view thereof.

Referring more particularly to the drawings, 1 designates a cabinet, being the customary cabinet of phonograph machines and provided with a top 2, above which lies the 60 rotary table 3 for receiving the disk records. In accordance with the usual practice, the table 3 is supported and rotated by a vertically disposed shaft 4 which passes down through the top 2 and is suitably journaled 65 therein.

According to the invention we provide a driving disk 5 on the lower end of the shaft 4 housed within the cabinet 1 and lying preferably in spaced relation beneath the 70 top 2; and with this driving disk 5 is engaged a friction gear 6 fixedly mounted upon the projecting shaft 7 of a motor 8, which, for convenience, is preferably an electric motor. Suitable leads are brought 75 to the motor from a plug and socket or other source of electric current. The motor is supported with the friction gear 6 for a sliding movement within the cabinet, to the end that such friction gear 6 may progress along 80 a radial line with respect to the driving disk 5 as becomes necessary in varying the speed of the rotary table 3. The friction wheel 6 and the motor 8 thus form a combined unit which move together and are 85 thus compactly assembled and made easily shiftable, and at the same time the weight of the motor 8 adds stability to the friction gear 6 and the device dispenses with such arrangements as keys to permit the sliding 90 of the friction gear 6 upon the motor shaft.

The motor is, in this instance, supported by arms 9 and 10 which engage with opposite sides thereof and are preferably four in number, two of such arms being disposed 95 at each side of the motor. The arms are provided with flanges 11 and 12 at their upper ends to be slidably received in the downwardly offset portions of Z-shaped guides 13 and 14 which are bolted or otherwise secured to the under surface of the top 2 of the phonograph cabinet.

Cross rails 15 and 16 are connected between the upper ends of the arms 9 and 10, as best seen in Figs. 3 and 4, in order to hold the arms properly spaced so that they will not be apt to bind in the guides 13 and 14, and at the same time to knit the whole structure together in a framework which will slide as a whole in the guides. Moreover, the rail 15 affords a means of connection of the framework to an operating rod 105 110

17 projecting through the horizontal wall of the cabinet and being slidable therein. An operating knob or head 18 is provided on the outer end of the rod 17 and a spring 5 rack 19 is provided beneath the rod 17 to be engaged with a tooth 20 on the exterior of the cabinet.

In operation, the motor 8 turns the friction gear 6, and by reason of the engagement of 10 the latter with the undersurface of the disk 5, the latter is rotated at a proportional speed and drives the rotary table 3 which carries the disk around beneath the needle of the phonograph.

15 It is well known in this art that a nice adjustment of the speed is required in order to secure the proper reproduction as to pitch of the piece, and also to accord with the tempo of the same, and heretofore such adjustment has been quite generally made by 20 regulators upon the governors of spring motors which are usually employed to drive the most popular makes of phonographs. This is an inaccurate adjustment and a difficult one to make at best. With the arrangement shown, a large range of adjustment can be had and one that may be nicely effected by the mere pushing in of the rod 17 or the withdrawing of it to a suitable 25 distance. In this way the friction gear 6 is made to progress nearer to or farther away from the center of the disc 5 and thus vary the proportion of speed at which the latter is driven. The guide construction 30 affords an easy path of adjustment and the motor 8 adds its weight to that of the friction gear and gives the construction a stability that it would otherwise not have.

It is obvious that various changes and 40 modifications may be made in the details of construction and design of the above specifically described embodiment of this invention without departing from the spirit thereof, such changes and modifications 45 being restricted only by the scope of the following claims.

What is claimed is:—

1. In a phonograph, an enclosing cabinet, a rotatable table arranged above the cabinet, 50 an operating disk arranged within the enclosing cabinet and connected to said turn table, a guideway arranged in the enclosing

cabinet in radial alignment with said disk, a carriage on the guideway, a motor mounted on the carriage and having a shaft projecting radially with respect to the disk and in over-lapping relation thereto, a drive member carried by the shaft and arranged to engage the side of said disk, and a shifting member slidably mounted through the wall 55 of said enclosing cabinet and connected to said carriage and projecting over the wall of said cabinet whereby the shifting member may be manually operated for sliding the carriage with its motor and gear member 60 relatively to the disk.

2. In a phonograph, a cabinet closed on its sides and top and housing therewithin a motor chamber, a turn table extending above the cabinet for receiving a record, drive 70 means in connection with the turn table, but lying within the motor chamber and entirely enclosed by said cabinet, a motor movable in said motor chamber and entirely within the cabinet for varying the speed of the 75 rotary table, a carriage for supporting said motor, guide means within the upper portion of the motor chamber for slidably suspending said carriage, operating means directly connected with the carriage and extending through a side wall of the cabinet to the exterior thereof and adapted for sliding movement by the hand of the operator, and co-operating parts on the casing and said operating means for securing the latter 80 in an adjusted position.

3. In a phonograph, a cabinet, a rotary table for the disk record upon the cabinet, a shaft for turning and supporting the table passing through the top of the cabinet, a 90 driving disk on the shaft within the cabinet, a friction gear engaging the under surface of the disk, an electric motor, having a shaft fixedly receiving said friction gear, a pair of parallel guideways secured beneath the top of the cabinet, a framework for supporting the motor and gear slidably horizontally in said guideways, an actuating rod extending from the framework through the wall of the cabinet, and means engaging 100 the rod for holding the motor and gear in an adjusted position, substantially as described.

ROBERT LEWIS HOLIMAN.

JOHN WORTH COLLINS.
